PROCESS FOR PRODUCING WATER GAS
FREE FROM TAR AND HYDROCARBONS

Franz Volk, Vienna, Austria

Application May 8, 1937, Serial No. 141,542
In Austria November 2, 1936

2 Claims. (Cl. 48—202)

This invention relates to a process for producing water gas free from tar and hydrocarbons, from bituminous fuels. Water gas generators surmounted by a distilling chamber and connected to a superheater are already known. In such generators the fuel is carbonized or distilled by the hot water gas generated in the gasifying chamber of the generator and rising into the distilling chamber, whereby this water gas is mixed with tarry vapours and distillation gases. For certain purposes, however, such admixtures of the water gas are objectionable and undesired. Moreover, in such generators the extent of the distillation of the fuel depends on the sensible heat of the water gas produced in the gasifying chamber. With the use of fuels having a high degree of moisture or a low percentage of fixed carbon, this heat is not sufficient to effect a sufficient distillation of the coal.

It has been already proposed to generate the water gas in alternating directions and to exhaust by suction the volatile distillation products from the distilling chamber during the upruns and to pass these distillation products through the superheater into the fire zone of the gasifying chamber in order to decompose the tar and the hydrocarbons. During the downruns the steam previously superheated in the superheater is passed from above to below through the distilling chamber and then together with the volatile distillation products through the gasifying chamber. According to this process, the fuel is distilled in a very incomplete manner since only the superheated steam is passed through the distilling chamber, the sensible heat of this steam not being sufficient to dry and to distill the fuel in a satisfactory manner. Furthermore, in this period the steam is passed through the gasifying chamber in the same direction as the fuel moves therethrough, whereby the steam is cooled at the upper cold fuel layers to such an extent that in the lower hot fuel zones the temperature gradient between the steam and the fuel, required for the heat transfer from the first to the latter is no more available.

By the present invention the production of a water gas free from tar and hydrocarbons, from bituminous fuels is made possible and the disadvantages of the methods known heretofore are obviated by distilling the fuel during the upruns as well as during the downruns by means of a circulating gas stream, the water gas produced in the gasifying chamber being discharged from the generator separately from the distillation gases not decomposed. During the upruns

the gas circulation is performed between the superheater, the gasifying chamber and the distilling chamber, whilst during the downruns, this circulation is performed merely between the superheater and the distilling chamber. The circulating gas always passes through the distilling chamber in counter-current relatively to the fuel so that the best transfer of heat is obtained. Furthermore the quantity of the circulating gas per time unit may be regulated according to the degree of moisture of the fuel and to the heat required for the distillation thereof so that it is possible to use fuels which are moist and difficult to gasify, no condensation of tarry vapours or steam occurring in the upper cold fuel layers.

By the new process the distillation gases and therefore also the tar contained therein are decomposed to form water gas. In some cases, however, it may be desirable for the sake of economy to recover the tar contained in the coal instead of decomposing the same to water gas. This is effected by separating the tar from the circulating gas after the latter leaves the distilling chamber and before it enters into the superheater.

If a tar production as complete as possible is desired this production may be performed also during the hot air blast period by passing a portion of the blast gases through the distilling chamber and then, mixed with the volatile distillation products, through the tar separator in which the tar is separated, the residual gases passing through the superheater which is heated by them.

In the accompanying drawing, an apparatus for carrying out the process according to the invention is diagrammatically illustrated by way of example.

The generator 1 comprises the gasifying chamber 2 surmounted by the distilling chamber 2'. 3 designates a superheater working according to the regenerative principle and 4 designates a steam injector effecting the gas circulation. Instead of this injector however, a fan or blower 45 of any desired construction may be provided.

At first, the hot air blast period is performed in the generator 1 by forcing air through the opened air valve 5 and the pipe 6 into the gasifying chamber 2. The blast gases flow through the valve 7 into the superheater 3 and are burnt in the latter by secondary air supplied from the pipe 8 through the valve 9 and, if required, also through the valve 9'. By this means the brick work of the superheater is heated up to a high

temperature. The combustion gases escape from the superheater 3 through the valve 10.

After the blast period, an uprun is effected. In this period the valves 5, 7, 9, 9' and 10 are closed and the valves 11, 12, 13 and 14 opened. Steam is supplied through the valve 11 and is passed through the injector 4 and the pipe 15 into the superheater 3 wherein it is highly superheated by the glowing brick-work thereof, and then flows through the valve 12 and the pipe 6 into the gasifying chamber 2. In this chamber water gas is generated by the contact between the steam and the hot coke, this water gas being discharged from the generator through the valve 13 and the pipe 16. At the same time the steam entering into the pipe 15 from the injector 4 exerts a suction action in the direction of the arrow x, whereby a gas circulation is caused along the elements 4, 15, 3, 12, 6, 2, 2', 14, 4. The volatile distillation products carried away by and with the circulating gas from the distilling chamber 2' are decomposed to water gas, as they pass through the fire zone of the gasifying chamber 2. The gas stream flowing from the gasifying chamber 2 into the distilling chamber 2' in the path of the circulation described above prevents the distillation gases coming from the distillation chamber 2' from being admixed with the water gas which is discharged at 13 from the generator 1. On the other hand by this flow of the gases an amount of heat sufficient for a complete distillation of the coal is transported into the distilling chamber 2'. The intensity of the gas circulation and therefore also the amount of heat transferred into the distilling chamber 2' may be varied, as required, by regulating the pressure of the steam supplied to the injector 4, or when the fan or blower is used, by regulating the speed of the same.

Now follows the downrun during which the valves 17 and 7 are opened and the valves 12 and 13 closed. The steam supplied through 11, 4 and 15 passes now through the upper part of the superheater 3 where it is superheated, and enters then through the valve 1 into the gasifying chamber 2 through which it passes from above to below. Thereby water gas is produced which leaves the generator 1 through the valve 17 and the pipe 16. At the same time, under the influence of the injector 4 a circulation is performed along the elements 4, 15, 3, 7, 2, 2', 14, 4 whereby heat is transferred from the superheater 3 into the distilling chamber 2' and the fuel is distilled thereby. A portion of the distillation gases entering together with the steam through the valve 1 into the gasifying chamber 2 is branched off from the circulating gas and passes through the gasifying chamber 2 from above to below. By this means not only the steam, but also the distillation gases are decomposed to water gas in the fire zone of the gasifying chamber, this water gas leaving the generator through the valve 17. It will be seen therefore that also in this period the discharged water gas does not contain distillation gases.

If it is desired to obtain tar from the distilla-

tion gases a tar separator 18 of known construction inserted into the circular path between the distilling chamber 2' and the superheater 3 is set into operation. For this purpose the valves 19 and 20 are opened and the valve 14 is closed. Alternatively, however, the injector or blower 4 may be omitted in which case the gas is circulated only by means of the blower 18. During the gas circulation which takes place in the uprun and downrun in the described manner the tar is separated from the circulating gas and is discharged from the accumulating device 18 into a container (not illustrated).

It is moreover possible to pass during the hot air blast period a portion of the blast gases from the gasifying chamber 2 through the distilling chamber 2' into the tar separator 18 and then, after freeing this portion from tar, through the injector 4 and the pipe 15 into the superheater 3. In the latter the blast gases are burnt by means of secondary air supplied through the valve 9' and the combustion gases escape through the valve 10.

What I claim is:

1. A process for producing water gas from bituminous fuels in a generator having a gasifying chamber and a superimposed distilling chamber, and having a superheater connected thereto, which comprises alternately hot air blasting, making a steam uprun and making a steam downrun, circulating during said uprun the gases from the distilling chamber through the superheater and the fire zone of said gasifying chamber into the generator and discharging the water gas after having passed the gasifying chamber and before having entered into the distilling chamber, and circulating during said downrun the gases from said distilling chamber through said superheater into the generator at the junction zone between said both chambers and discharging the water gas after having passed the gasifying chamber.

2. A process for producing water gas from bituminous fuels in a generator having a gasifying chamber and a superimposed distilling chamber, and having a superheater connected thereto, which comprises alternately hot air blasting, making a steam uprun and making a steam downrun, passing during the hot blast period at least a part of the blast gases from the gasifying chamber through the distilling chamber, then separating the tar of the blast gases and finally admitting these gases into said superheater and burning them therein, circulating during said uprun the gases from the distilling chamber through the superheater and the fire zone of said gasifying chamber into the generator and discharging the water gas after having passed the gasifying chamber and before having entered into the distilling chamber; and circulating during said downrun the gases from said distilling chamber through said superheater into the generator at the junction zone between said both chambers and discharging the water gas after having passed the gasifying chamber.
